BURNER

Clay C. Simpson, San Angelo, Tex.

Application November 9, 1938, Serial No. 239,706

2 Claims. (Cl. 158—53)

This invention relates to a burner, and it is one object of the invention to provide a device of this character of such construction that either gasoline or kerosene may be burned, improved means being provided for converting the liquid fuel into a gas and then mixing the gaseous fuel with air to form a combustible mixture.

Another object of the invention is to so form the device that, when it is in use, the liquid fuel during its conversion into a gas will be passed through a tortuous passage about a tube constituting a combustion chamber and the fuel subjected to heat in such a manner that it will be very effectively transformed into a hot gas which then passes through a pipe line and is delivered into the combustion chamber.

Another object of the invention is to provide a device of this character having means for draining off liquid fuel at the front end of the burner when found necessary.

It is another object of the invention to provide a burner having a fuel pan wherein fuel may be burned as a preliminary heating means for the body into which the liquid fuel is delivered and transformed into a gas.

Another object of the invention is to provide an improved type of hood which serves as a shield for the tubular body and prevents atmospheric cooling of the body when the burner is in use.

Another object of the invention is to provide a burner including a tubular body and a tubular combustion chamber together with plates or disks mounted about the inner tube in such a manner that they will be securely but detachably held in place and, when in place, provide the tortuous pathway wherein the liquid fuel is transformed into a hot gaseous fuel.

The invention is illustrated in the accompanying drawings, wherein:

Figure 1 is a sectional view taken longitudinally of the burner in a vertical plane.

Figure 2 is a transverse sectional view taken along the line 2—2 of Figure 1, and

Figure 3 is a perspective view of two of the disks carried by the inner tube.

The body 1 of this burner consists of a tube of a predetermined length and diameter formed of strong metal. Within the tubular body is disposed an inner tube 2 which is also formed of strong metal having its end portions externally threaded so that disks 3 and 4 may have their annular flanges or necks 5 and 6 screwed upon end portions of the inner tube and thus securely but removably mount the end disks or closures upon end portions of the inner tube. These end disks or closures are of the proper diameter to fit snugly within the tubular body 1 and close the ends of a chamber 7 about the inner tube. Fuel is to be passed through the conversion chamber

1 and converted from a liquid form into a gaseous state, and in order to cause the fuel to move in a tortuous path through this conversion chamber, there have been provided a plurality of disks 8 and 8' which fit snugly about the inner tube 2 and are formed with collars 9 to provide a good fit about the inner tube and serve to hold the disks in proper spaced relation to each other longitudinally of the inner tube and the tubular body as well as preventing these disks from tilting longitudinally of the inner tube out of their proper angular relation to the tube and the body. These disks are applied after one of the end disks has been applied and when the second end disk is screwed onto the tube all of the disks will be firmly held in place. When, however, it is necessary to remove any of the disks for thorough cleaning or replacement thereof, it is merely necessary to unscrew one of the end disks after withdrawing the tube and the disk from the body and the disks 8 and 8' may then be easily slid longitudinally off the tube. The end disks 3 and 4 may be securely but removably mounted within ends of the body 1 in any desired manner, but they are preferably welded therein so that they will be firmly held in place and a tight joint formed between margins of these disks and the walls of the tubular body. Small openings or perforations 10 and 11 are formed in the disks 8 and 8', and while these disks are of a duplicate formation, they will be so secured upon the tube that, when the tube and the disk are mounted in the tubular body 1, the perforations 10 of the disk 8 will be above the tube and the perforations 11 of the disk 8' below the tube. Therefore, the fuel must follow a tortuous pathway formed in the tubular body about the inner tube as it flows through the space 7 and the liquid fuel which enters through the pipe line 12 will be very effectively converted into a hot gas which passes out through the pipe line 13.

In order to effect a preliminary heating of the body 1, there has been provided a heating pan 14 which is disposed under the body and provided with upwardly extending arms 15 formed of metal strips which have their upper end portions offset inwardly, as shown in Figure 3, and secured against opposite sides of the body 1 by screws 16. This pan is to hold a liquid fuel which, when ignited, will cause the body 1 to be heated to such a temperature that, when the valve 17 of the pipe line 12 is opened and liquid fuel flows through this pipe line into the front end of the space or chamber 7, it will make contact with hot metal and be converted into a gas. This gas will be more in the nature of a vapor, and as it follows the tortuous pathway into which the space or chamber 10 is formed by the baffle plates or disks, it will be subjected to heat for such a length of time that it will be converted

into a gaseous state in a very effective manner and a hot dry gas delivered into the pipe line 13. This pipe line extends longitudinally of the burner, and at the forward end of the burner extends downwardly, as shown at 18, and then towards the center tube 2, as shown at 19. This portion 19 of the pipe line 13 extends in axial alinement with the tube and carries a nozzle 20 from which a jet of gas is discharged into the elongated combustion chamber 21 formed by the tube. As the gas rushes through the combustion chamber 21, air will be drawn into this chamber to mix with the gas and form a combustible mixture, and when this combustible mixture is lighted, the tube 2 together with the disk carried thereby and the tubular body will be heated to a very high temperature and the fuel which continues to flow into the chamber 1 will be quickly converted into a hot and dry gas. A drain pipe 22 controlled by a valve 23 leads from the bottom of the chamber 18 adjacent the front end of the body 1 so that in case too much liquid fuel is initially fed into the conversion chamber or the valve 17 is not shut tightly when the burner is not in use and liquid fuel leaks through the pipe line 12, this fuel may be drawn off through the drain pipe.

It is desired to shield the body 1 from atmospheric air currents which are liable to cool it to some extent when the burner is in use. Therefore, there has been provided a metal hood or shield 24 formed of sheet metal which is bent so that this hood or shield may be disposed in straddling relation to the tubular body, as shown in Figure 2. The upper portion of this hood or shield rests upon sleeves 25 provided about the vertically disposed portions 12' and 13' of the pipe line 12 and 13 so that the upper portion of the hood will be supported in the desired spaced relation to the tubular body. The depending side walls 26 of the hood are welded or otherwise firmly secured against the metal strips or arms 15, and in these side walls are formed openings 27 which constitute ventilating openings.

When this burner is in use, it is set up as shown in Figure 1, and a quantity of liquid fuel poured into the heating pan 14. This fuel is then ignited and allowed to burn so that the tubular body will be thoroughly heated. When the fuel in the pan is almost consumed, the valve 17 is opened and liquid fuel will flow through the pipe line 12 into the front end of the conversion chamber 1, and upon striking the hot wall of the body, it will be converted into a gas or vapor which flows through the openings 10 at the top of the first baffle plate or disk 8 with sufficient force to cause it to strike against the adjacent baffle plate or disk 8'. The gas or vapor then moves downwardly and through the opening 11 of the disk 8' and upon striking the next disk 8, it will flow upwardly and through the opening 10 of this disk. This movement is continued as the vapor or gas follows the tortuous path defined by the disk, and upon reaching the rear end of the conversion chamber, the fuel will have been transformed or converted into a gas which is hot and dry. This gas flows upwardly into the pipe line 13 and after following this pipe line is discharged through the nozzle 20 into the combustion chamber 21 where it will mix with air sucked into the combustion chamber by the jet of gas and the gas and air will mix in the combus-

tion chamber to form a combustible fluid. This combustible fluid is then ignited and a very hot flame will be produced which may be employed for any purpose for which the burner is designed and will serve very effectively to highly heat the tube 2, the disk and the body 1 of the burner. In view of the fact that the burner is shielded by the hood 24, undesired cooling by atmospheric air currents will be prevented. When operation of the burner is no longer desired, it is merely necessary to close the valve 17 and the flow of liquid fuel through the pipe line 12 will be shut off. When draining is necessary, the valve 23 may be opened and any fuel which has accumulated between the end disks 3 and the first disk or baffle 8 will flow out through the drain pipe 22. When it is desired to thoroughly clean the burner or replace any of the baffle plates or disks, the end disks 3 and 4 are released from their connections with the walls of the tubular body 1 and the tube 2 and the disk carried thereby may then be slid longitudinally out of the body. One of the end disks may then be unscrewed and the baffle plates or disks slid longitudinally off the tube. A thorough cleaning may then be performed including reborning of the perforations 10 and 11 if necessary and the device reassembled, new baffle disks being applied to the tube if found necessary.

Having thus described the invention, what is claimed as new is:

1. A burner of the character described comprising a tubular body, a tube extending longitudinally through said body axially thereof, end disks removably carried by portions of said tube and fitting snugly into end portions of said body to provide closures for ends of the space within the body about the tube, the said space constituting a conversion chamber, other disks fitting about said tube and each being formed with integral sleeves fitting snugly about the tube between the disks to maintain the disks in spaced relation to each other longitudinally of the tube and divide said conversion chamber into a plurality of sections communicating with each other through openings formed through the disks, the first-mentioned disks constituting means for holding the last-mentioned disks firmly in place about the tube, means for delivering liquid fuel into the forward end portion of the conversion chamber, and a conduit leading from the rear end portion of the conversion chamber for conducting gaseous fuel therefrom and delivering the same into the front end of said tube for mixing with air in the tube and forming a combustion mixture.

2. In a burner of the class described, a body, a tube extending longitudinally through the body, disks fitted about the tube and each being formed with sleeves fitting snugly about the tube between the disks to maintain the disks in spaced relation to each other, the space between the tube and body defining a conversion chamber and the disks dividing said conversion chamber into a plurality of sections, means for leading liquid fuel into the conversion chamber at one end thereof, said liquid fuel being converted to gaseous fuel within the chamber, and means for leading gaseous fuel from the conversion chamber to a burner.
